United States Patent

Des. 235,716
Patented July 8, 1975

235,716

CHEST

Aaron Donner, Weston, Conn., assignor to
The Lane Company, Inc.

Filed July 10, 1974, Ser. No. 487,376

Term of patent 14 years

Int. Cl. D6—04

U.S. Cl. D6—154

The figure is a front and left side perspective view of a chest showing my new design, the right side being substantially identical to the left.

The top and rear of the chest are plain and unornamented.

I claim:

The ornamental design for a chest, as shown and described.
